UNITED STATES PATENT OFFICE.

OTTO J. GROEHN, OF DETROIT, MICHIGAN, ASSIGNOR TO CLAYTON AND LAMBERT MANUFACTURING COMPANY, OF DETROIT, MICHIGAN, A CORPORATION OF MICHIGAN.

FLAME-Straightening Torch Burner.

Application filed April 25, 1921. Serial No. 464,333.

To all whom it may concern:

Be it known that I, OTTO J. GROEHN, a citizen of the United States of America, residing at Detroit, in the county of Wayne and State of Michigan, have invented certain new and useful Improvements in Flame-Straightening Torch Burners, of which the following is a specification, reference being had therein to the accompanying drawings.

10 This invention relates to burners and refers more particularly to burners of the type known as torch burners for blow torches or the like.

It is one of the objects of the invention to provide an improved burner of the general character above referred to which will direct the flame from the forward end of the combustion chamber in the proper direction. Other objects of the invention are, to provide a construction which will be convenient for location with other parts of the burner and which will permit of a simplified and improved construction of burner. The invention also resides in such features of construction and arrangements and combinations of parts as will more fully hereinafter appear.

In the drawings:

Figure 1 is a side elevation view partly in section;

Figure 2 is a top plan view of the parts shown in Figure 1;

Figure 3 is a sectional view on the line 3—3 of Figure 1;

Figure 4 is a vertical sectional view on the line 4—4 of Figure 1.

Describing in detail the particular embodiment of my invention shown in the drawings, A designates a torch burner connected by a fitting B to the tank B' in any suitable manner. The burner comprises a combustion chamber C in which the vaporized fuel from the nozzle D is mixed with air and burned, the flame being projected from the forward end C' of the combustion chamber. The supply of fuel from the tank B' to the discharge nozzle D is through a vaporizing chamber or passage E past the control valve F and through the passages F' and F² to the nozzle. The outlet opening of the latter is kept free from accumulation of carbon or other obstructions by means of a clean-out member or pin G carried by the stem G'

which at its outer end terminates at a hand wheel G². This clean-out pin is preferably so arranged as not to perform the functions of a valve, owing to the difficulty of maintaining a valve seat and valve at this particular portion of the burner. For this reason the valve F is located at a point more remote from the nozzle D and is carried by an adjustable stem H having a hand wheel H'. It will be noticed that in the particular construction shown in the drawings the stem H' is diagonally downwardly and sidewardly inclined thus permitting the hand wheel H' to be relatively close to the hand wheel G² without interfering with the latter. This novel arrangement also permits the use of the two stems and hand wheels G' and G² and H and H' without in any way interfering with the convenient location of the pump handle I.

In torches of this general character difficulty is often encountered in discharging the flame from the forward end of the combustion chamber to the exact direction desired. Obviously if the discharge nozzle is out of axial alignment with the discharge end of the combustion chamber unequal combustion will take place and in many cases the flame is unequally distributed at the outlet end of the nozzle. The present novel construction of combustion chamber not only improves the combustion within the chamber but also serves to straighten out the flame and insure its proper delivery at the discharge end C'. As shown in Figure 1 the combustion chamber C is provided with baffles J, J', J² and J³, each of which extends inwardly and preferably has its rear wall forwardly inclined as at K. It will also be noticed that the baffles or straightening flanges J and J' are of such size that their ports L and L' are of smaller diameter than the port L² and that this port L² while larger than the ports L and L' is smaller than the port L³ in the forward baffle or straightening flange. Also the combustion chamber is provided with air inlet ports or openings M, M', M² and M³ which are located preferably between the respective baffles. The entire arrangement is one which because of the baffling arrangement insures complete combustion and the delivery of the hottest flame at the forward or discharge

end C' and also of the straightening out of the flame so that it is directed axially of the combustion chamber C and in a desired direction at the time it passes between the parallel walls N of the forward end C'.

As shown in detail in Figures 3; these inwardly projecting flanges J, J', J² and J³ are preferably formed as substantially circular flanges but having a recessed portion 10 O at the lower side. However, except as ultimately set forth in the claim I do not desire to limit the invention to the particular details of construction shown:

What I claim as my invention is:

15 In a burner for blow torches or the like, the combination with a combustion chamber

having a fuel discharge nozzle at the rear portion; of an adjustable clean-out member for said discharge nozzle, a valve beneath and to one side of the nozzle and clean-out member for controlling the supply of fuel to said nozzle; and a plurality of parallel baffles disposed in said chamber and having ports formed therein to direct the flame toward the forward end of said chamber, said baffles being spaced from said discharge nozzle and said chamber having air inlet ports formed therein between said baffles. 20 25

In testimony whereof I affix my signature.

OTTO J. GROEHN.
